FIG. 4 is a bottom view of the tray of FIG. 1;

FIG. 5 is an elevation view of one of the opposing short sides of the tray of FIG. 1;

FIG. 6 is an elevation view of one of the opposing long sides of the tray of FIG. 1;

FIG. 7 is a cross-sectional elevation view along line 7-7 shown in FIG. 3;

FIG. 8 is a cross-sectional elevation view along line 8-8 shown in FIG. 3;

FIG. 9 is a top perspective view of a second embodiment for a tray with finger pockets showing our new design;

FIG. 10 is a bottom perspective view of the tray of FIG. 9;

FIG. 11 is a top view of the tray of FIG. 9;

FIG. 12 is a bottom view of the tray of FIG. 9;

FIG. 13 is an elevation view of one of the opposing short sides of the tray of FIG. 9;

FIG. 14 is an elevation view of one of the opposing long sides of the tray of FIG. 9;

FIG. 15 is a cross-sectional elevation view along line 15-15 shown in FIG. 11;

FIG. 16 is a cross-sectional elevation view along line 16-16 shown in FIG. 11;

FIG. 17 is a top perspective view of a third embodiment for a tray with finger pockets showing our new design;
FIG. 18 is a bottom perspective view of the tray of FIG. 17;
FIG. 19 is a top view of the tray of FIG. 17;
FIG. 20 is a bottom view of the tray of FIG. 17;
FIG. 21 is an elevation view of one of the opposing short sides of the tray of FIG. 17;
FIG. 22 is an elevation view of one of the opposing long sides of the tray of FIG. 17;
FIG. 23 is a cross-sectional elevation view along line 23-23 shown in FIG. 19;
FIG. 24 is a cross-sectional elevation view along line 24-24 shown in FIG. 19;
FIG. 25 is a top perspective view of a fourth embodiment for a tray with finger pockets showing our new design;
FIG. 26 is a bottom perspective view of the tray of FIG. 25;
FIG. 27 is a top view of the tray of FIG. 25;
FIG. 28 is a bottom view of the tray of FIG. 25;
FIG. 29 is an elevation view of one of the opposing short sides of the tray of FIG. 25;
FIG. 30 is an elevation view of one of the opposing long sides of the tray of FIG. 25;
FIG. 31 is a cross-sectional elevation view along line 31-31 shown in FIG. 27;
FIG. 32 is a cross-sectional elevation view along line 32-32 shown in FIG. 27;
FIG. 33 is a top perspective view of a fifth embodiment for a tray with finger pockets showing our new design;
FIG. 34 is a bottom perspective view of the tray of FIG. 33;
FIG. 35 is a top view of the tray of FIG. 33;
FIG. 36 is a bottom view of the tray of FIG. 33;
FIG. 37 is an elevation view of one of the opposing short sides of the tray of FIG. 33;
FIG. 38 is an elevation view of one of the opposing long sides of the tray of FIG. 33;
FIG. 39 is a cross-sectional elevation view along line 39-39 shown in FIG. 35;
FIG. 40 is a cross-sectional elevation view along line 40-40 shown in FIG. 35;
FIG. 41 is a top perspective view of a sixth embodiment for a tray with finger pockets showing our new design;
FIG. 42 is a bottom perspective view of the tray of FIG. 41;
FIG. 43 is a top view of the tray of FIG. 41;
FIG. 44 is a bottom view of the tray of FIG. 41;
FIG. 45 is an elevation view of one of the opposing short sides of the tray of FIG. 41;
FIG. 46 is an elevation view of one of the opposing long sides of the tray of FIG. 41;
FIG. 47 is a cross-sectional elevation view along line 47-47 shown in FIG. 43;
FIG. 48 is a cross-sectional elevation view along line 48-48 shown in FIG. 43;
FIG. 49 is a top perspective view of a seventh embodiment for a tray with finger pockets showing our new design;
FIG. 50 is a bottom perspective view of the tray of FIG. 49;
FIG. 51 is a top view of the tray of FIG. 49;
FIG. 52 is a bottom view of the tray of FIG. 49;

FIG. 53 is an elevation view of one of the opposing short sides of the tray of FIG. 49;
FIG. 54 is an elevation view of one of the opposing long sides of the tray of FIG. 49;
FIG. 55 is a cross-sectional elevation view along line 55-55 shown in FIG. 51;
FIG. 56 is a cross-sectional elevation view along line 56-56 shown in FIG. 51;
